US00D913268S

(12) **United States Design Patent** (10) **Patent No.:** **US D913,268 S**
Seo (45) **Date of Patent:** **** Mar. 16, 2021**

(54) **MOBILE PHONE**

(71) Applicant: **Samsung Electronics Co., Ltd.**, Suwon-si (KR)

KR 30-0698312 6/2013
KR 30-0725377 1/2014

(Continued)

(72) Inventor: **Jaehun Seo**, Suwon-si (KR)

(73) Assignee: **SAMSUNG ELECTRONICS CO., LTD.**, Suwon-si (KR)

(**) Term: **15 Years**

(21) Appl. No.: **29/670,182**

(22) Filed: **Nov. 14, 2018**

Related U.S. Application Data

(62) Division of application No. 29/591,548, filed on Jan. 20, 2017, now abandoned.

(57) **CLAIM**

The ornamental design for a mobile phone, as shown and described.

DESCRIPTION

FIG. 1 is a front perspective view of a mobile phone showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The evenly-spaced dashed broken lines in the drawings depict portions of the mobile phone that form no part of the claimed design. The dot dash broken lines in the figures define the boundaries of the claimed design and form no part thereof.

1 Claim, 7 Drawing Sheets
